(57) **CLAIM**

The ornamental design for an electric hair clipper, as shown and described.

DESCRIPTION

FIG. 1 is a top perspective view of an electric hair clipper, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

(Continued)

FIG. 7 is a bottom view thereof.
The broken lines in the drawings depict portion of an electric
hair clipper and form no part of the claimed design.
